United States Patent Office.

E. K. HAYNES, OF HANOVER, NEW HAMPSHIRE.

Letters Patent No. 78,084, dated May 19, 1868.

IMPROVEMENT IN LAMP-SHADES.

The Schedule referred to in these Letters Patent and making part of the same.

TO ALL WHOM IT MAY CONCERN:

Be it known that I, E. K. HAYNES, of Hanover, in the county of Grafton, and State of Massachusetts, have invented an Improved Lamp-Shade; and I do hereby declare that the following, taken in connection with the drawings which accompany and form part of this specification, is a description of my invention sufficient to enable those skilled in the art to practise it.

My invention relates to the construction of a lamp-shade, to be supported directly upon a lamp-chimney, by hanging it upon the top of the same.

United States Letters Patent, No. 71,168, were granted to me, November 19, 1867, on a lamp-shade supported upon a frame of wires, and capable of adjustment thereon, by sliding this wire frame, being fixed to a ring made to fit upon the cap or burner of the lamp.

My present invention relates to a provision for hanging, from the top of the chimney, a sliding shade, similarly supported by and upon a frame of wires.

In United States Letters Patent, No. 66,576, of July 9, 1867, there is shown a shade supported on a single wire, which wire has a hook at its upper end, by which to suspend it from the top of the chimney.

Such construction is imperfect, in that it furnishes no adequate provision for properly holding a curved shade, or for keeping such a shade concentric to the lamp-chimney.

In my improved shade, I mount the screen upon a frame made up of two uprights, bent and joined at their lower ends, and each having a hook at its upper end, the two hooks keeping the shade from swinging, and the two wires affording a firm support for a curved screen, through staples, upon which the wires run, enabling the screen to be adjusted, as to height, upon the frame.

It is in this improved construction that my invention consists.

The drawing represents, in perspective, a shade embodying my invention. *a* denotes the screen. *b*, a wire frame, so bent as to form two vertical rods, *c*, bent at their lower ends to form two arms, *d*, which, with their connecting-wire, *e*, rest against the side of the chimney, (seen by dotted lines,) and hold the screen at proper distance from the glass.

The wires pass through staples, *f*, fixed to the screen *a*, and as the frame made by the wires is somewhat rigid, the curved form of the screen is not only preserved, but the screen is kept from twisting or swinging upon the frame, as it inclines to do when supported upon only one wire.

Near their upper ends, the wires are bent towards each other, and, at its extreme end, each is bent over to form a hook, *g*, by the pair of which the screen is suspended from the chimney-top, as seen in the drawing.

I claim a lamp-shade, made up of a screen, supported upon two uprights, bent and joined at their lower ends, to connect them, and to support the screen at proper distance from the chimney, and bent and made hook-formed, at their upper ends, to suspend the screen from the top of the chimney, the screen sliding upon the frame, and being supported relatively thereto, substantially as described.

E. K. HAYNES.
